UNITED STATES PATENT OFFICE.

JOHN HARRIS, OF CLEVELAND, OHIO, ASSIGNOR TO CARBO-HYDROGEN COMPANY OF AMERICA, OF PITTSBURGH, PENNSYLVANIA, A CORPORATION OF DELAWARE.

CUTTING-TORCH.

1,217,119.

Specification of Letters Patent. Patented Feb. 20, 1917.

Application filed December 17, 1914. Serial No. 877,649.

To all whom it may concern:

Be it known that I, JOHN HARRIS, a citizen of the United States, residing at Cleveland, in the county of Cuyahoga and State of Ohio, have invented a certain new and useful Improvement in Cutting-Torches, of which the following is a full, clear, and exact description, reference being had to the accompanying drawings.

This invention relates to blow pipes, or torches, or burners which are designed with special reference to the so-called "cutting" or burning of steel and iron in and through the use of an excess of oxygen. It is the general purpose of this invention to provide a torch or burner of this character which shall be extremely efficient and economical in operation and one wherein the cutting or burning action can be concentrated along a narrow line, whereby the cutting can be accomplished with a minimum loss of metal and with the production of a minimum amount of "slag" along the edges of the cut. It is evident that a burner or blow pipe possessing the capability of operation above described is one which is particularly efficient as well as economical in the amount of fuel employed, since the amount of gas required for cutting a very narrow slot or slit is necessarily less than will be required in cutting a wider one.

A further object of the invention is to provide a burner or tool of the character above described which is extremely convenient of operation; also a burner or tool of this type wherein the capacity can be conveniently varied at will, by the use of interchangeable tips of varying capacities. A further and more limited object of the invention is to improve the construction of the oxygen injector; also to provide an improved construction of valve for the pipe or conduit which conducts the separate jet of oxygen for the cutting or burning operation. My invention consists further in certain details of construction whereby the foregoing results are accomplished and particularly to means whereby the flame may be concentrated and the propagation of the flame within the burner and the parts connected thereto will be prevented.

Still further and more generally speaking the invention will be defined as consisting of the combinations of elements embodied in the claims hereto annexed and illustrated

in the drawings forming part hereof wherein; Figure 1 is a side elevation of a burner torch or blow pipe constructed in accordance with my invention; Figs. 2 and 2^a represent, conjointly, a longitudinal central sectional view through the burner torch or blow pipe shown in Fig. 1; Fig. 3 is a rear end elevation of the same; Fig. 4 is a side elevation of the inner tubular member of the tip which is used with and forming part of the burner torch or blow pipe; Fig. 5 is a longitudinal sectional view through the outer member of said tip; while Figs. 6 and 7 are sectional details corresponding respectively to the lines 6—6, 7—7 of Fig. 2; Fig. 8 is a section on the line 8—8 of Fig. 2^a; and Fig. 9 is a sectional detail corresponding to the line 9—9 of Fig. 3.

The construction illustrated in the aforesaid drawing and described in detail herein-after comprises generally a burner head having passageways for oxygen and a combustible gas (as hydrogen) an injector nozzle coöperating with the oxygen passageway and arranged in proper relation to the combustible gas passageway, a detachable tip coöperating with and forming part of said head, pipes extending to the passageways in the head, a handle extending around said pipes, and valve mechanism associated with said handle whereby the proportions of the oxygen and combustible gas may be regulated and the supply of oxygen to the oxygen passageway may be conveniently turned off and on.

Describing by reference characters the various parts illustrated herein, A denotes generally the burner head, said head comprising a body *a* having a detachable tip *a'*. The body *a* comprises two branches which are preferably angularly disposed with reference to each other, the body being preferably a casting. For convenience of description, the burner or torch will be considered as being used in the position shown in Fig. 1 and the terms "top" and "bottom" will be used accordingly. The branch 1 at the front of the body *a* comprises an annular wall or shell having its lower end reduced and exteriorly threaded, as shown at 2, whereby the outer members of the detachable tips (to be described hereinafter) may be conveniently packed. The body *a* is provided with a wall forming the top of the chamber 3, which wall is bored out and

provided with an internal thread 4 for the reception of the inner member of the detachable tip, and from the upper end of the chamber thus formed by boring said wall, 5 extends a passageway 5, said passageway leading to the rear end of the burner head. The upper portion of the chamber 3 communicates with a passageway 6 which passageway is enlarged at its rear end and internally threaded, as shown at 7, this internally threaded part of the passageway extending to the rear end of the burner head. Within the threaded part of the passageway there is mounted an injector nozzle, 15 said nozzle comprising the front nozzle portion 8 and the rear reduced portion 9 having a head 10, said head being knurled and provided with a slot 11 for convenience of manipulation. A packing washer 12 may be provided between the head 10 and the adjacent rear end of the burner head. The nozzle proper 8 is provided with a central bore 13 extending from the front end to a transverse passageway 14 which is adapted 20 to communicate with a passageway 15 extending from the bore 7 to the rear end of the burner head. The front end of the nozzle is arranged above and substantially at the rear end of the passageway 16 which extends from the bore 7 to the rear end of the burner head. The injector 9 is conveniently removable from its passageway, enabling it to be replaced by other injectors, varying in capacity in accordance with the capacity of 25 a particular tip that may be used in connection with the burner head.

The detachable tip referred to hereinbefore comprises generally an outer frusto conical or tapered nozzle 17 and an inner tubular member 18 which may be conveniently connected by means of one or more pins indicated at 19 on Fig. 5 of the drawing. The inner member of the tip is provided at its upper end with an external thread whereby it may be threaded into the internally threaded bore 4, thereby securing the tip as a whole in place. The threaded end of the inner member is indicated at 20. At a suitable distance below this threaded end and within the top of the outer nozzle or member 17, the inner member is provided with a tapered projection 21 which is adapted to form a close fit with the inner wall of such outer member 17. This projection 21 is provided with a plurality of slots, which preferably extend from the outer surface inwardly as far as the body of the said inner member. Four such slots 22 are shown and each of these slots is preferably substantially rectangular in section, for a purpose to be explained hereinafter. At its lowermost end, the inner tip member is provided with a projection, indicated generally at 23, which projection extends from the body of said member as far as and forms a close fit with

the lower end of the inner wall of the outer member 17. The projection 23 is provided with a plurality of slots 24. Six such slots are shown, and these slots are also substantially rectangular in section. The construction of the tip, including the manner of forming the passageways for the mixture of gases supplied to the chamber 3 contributes materially toward the production of a concentrated flame of large heating efficiency whereby the rapid cutting or burning of a narrow slit through the metal is accomplished without slagging; also to the prevention of the propagation of flame through said passages and into the interior 75 of the burner and the parts connected therewith.

The particular shape of the passageways or slots formed in the projection 23 secures a concentrated preheating flame, which confines the cutting operation to a narrow slit and enables such a narrow slit to be cut with a minimum amount of slagging. Furthermore, the particular shape of these slots or passageways entrains a larger amount of 80 gas than is the case with slots of other shapes with which I am familiar, and keeps the preheating flame from blowing out under pressure.

It will be observed that the upper end of 95 the member 17 is of a diameter to form a comparatively close fit with the lower end of the shell 1. A non-leaking joint is provided between this outer member and the shell by means of a packing gland 25 threaded onto the lower end of the shell and containing packing 26 adapted to bear against the lower end of said shell and to be compacted thereagainst and into the seam or joint formed between said shell and the 100 member 17. It will be obvious that the tip shown herein may be replaced by others, similarly constructed, but having different capacities of bores and passageways for the gases. The rear end of the head A is shown 105 as connected to three pipes 27, 28 and 29, these pipes being arranged to discharge into the passageways 16, 15 and 5 respectively. The pipes are brought in close proximity to each other and extend through a front plate 110 30 and into the circular front end of a casting 31. A sleeve 32 unites the front end of said casting and the plate 30 and forms a handle. This handle, indicated generally at 115 B, affords convenient means for operating 120 the burner or torch. The casting 31 at the rear of the handle is provided with a bore 33 communicating with the pipe 27 and with the through passage 34 in a valve casing 35, said valve casing having a rotary valve 36 125 therein. The rear end of the valve casing is provided with a flexible tube B, said tube being for combustible gas (as hydrogen) through the valve casing. The rear casting 31 is provided with a hollow boss 37 having 130

a connection 38 for the flexible tube C which conducts oxygen to a chamber 39 having a lateral branch 40 which communicates with a passageway 41 leading through the valve seat 42. This valve seat is controlled by a valve (to be described in detail hereinafter) and, when the valve is open, the oxygen admitted to the chamber 39 can pass through the valve seat, chamber 43 and passageway 44 into the oxygen tube 28. The casting 31 is provided with a hollow cap 45 threaded thereinto and carrying a spring 46 the opposite end whereof surrounds one end 47 of a valve stem, said stem having a valve 48 thereon adapted to be pressed against the seat 49 by said spring. It will be observed that the seat 49 is of frusto conical shape, thereby to prevent the adherence of sediment thereto. The stem of the valve extends through one side of the casting, passing through a stuffing box comprising the packing 50 and the plug 51 threaded into the side of said casting. This plug forms a guide for the valve stem. 52 denotes an angle lever the short branch whereof is pivotally connected to the lugs 53 and the rear end of the casting 31 and the longer branch whereof extends across the projecting end of the valve stem and alongside the tubular handle 32, in position to be conveniently and, in fact, automatically grasped when the operator picks up the torch by the handle.

Reference has been made to the oxygen valve. This valve comprises a rotatable valve stem 54 which may be threaded into the outer end of the passage or chamber 43 and is there provided with the usual stuffing box 55. The outer end of this stem is provided with a hand wheel 56 while the inner end of the stem is reduced, as shown at 57, and provided with a spherical head 58. The needle point of the valve comprises a conical body 59 of such metal as is best adapted to resist the action of the particular fluid or gas with which the valve is to be employed. The end of this body opposite the point is preferably made in cylindrical shape, the internal diameter of the cylinder being substantially equal to the external diameter of the spherical head 58, whereby said head may enter the chamber or recess formed in the head of the valve point. The end of the sleeve thus formed is spun or otherwise pressed inwardly so as to inclose the spherical head, leaving a certain amount of lost motion or play between the end of the body and the reduced part of the valve stem 57. In operation the valve point will engage its seat 42 but, being rotatable with respect to the valve stem, the subsequent turning of the valve stem will not rotate the valve point but will, nevertheless, force it tightly against its seat. A sort of universal joint connection is thus provided between the valve stem and the valve point which

enables this point to find its seat irrespective of imperfect workmanship on the valve stem and in the coöperating portion of the seat. This also permits the operator to renew the valve points or needles from time to time, as occasion may require without the necessity for throwing away the entire valve body. Obviously this construction enables the operator to use for his needles or valve points an expensive metal, while reducing the cost of the valve as a whole by the employment of inexpensive metal in the remaining part. This construction possesses great advantages in connection with certain gases (such as hydrogen and oxygen) enabling valve points to be made from metals which are particularly well adapted to resist the action of such gases, but without the necessity of making the entire valve of such metal. A further advantage of this construction is that the valve point will not be worn by grinding upon its seat, as the valve point will not be rotated upon the seat through the rotation of the valve stem.

In operating the burner or torch in accordance with my invention, the valve bodies 36 and 54 are adjusted to such position as will insure the proper proportions of gases for the capacity of the particular tip that may be required. The converging jets of gases having been ignited, the oxygen for cutting or burning will be turned on by pressing the valve lever 52 toward the handle 32—an operation which is more or less automatically performed by grasping the handle. When it is desired to vary the capacity of the burner or tool, tips similar to that shown herein but of different capacity will be substituted, the valves 36 and 54 being adjusted in accordance with the capacity of such tips, and the cutting operation may be preceeded with.

The construction of the block or casting 31, with the arrangement of the passageways and the means for controlling the flow of fluid therethrough to the passages of the blow pipe, constitutes the subject matter of my application No. 140,111, January 2, 1917.

Having thus described my invention, what I claim is:

1. In a burner of the character described, the combination of a head comprising a shell having a chamber in its front or discharge portion, a central bore at the rear of said chamber and a bore or passageway communicating with said chamber in front of said central bore, a tip comprising an inner tubular member the rear end whereof coöperates with said central bore and a nozzle member surrounding and connected to the front or discharge portion of said tubular member, there being a passageway between said nozzle member and the bore of the tubular member, and means for connecting said tip to said head with the passageway in the nozzle mem- 130

- ber thereof communicating and coöperating with said chamber and with the inner tubular member thereof in operative relation to said central bore.
2. In a burner of the character described, the combination of a head having a centrally arranged bore, a seat in front of said bore, a chamber in front of said seat, a supply connection leading to said chamber, a removable tip comprising an inner tubular member the rear end whereof coöperates with said seat, a nozzle member surrounding the front portion of said tubular member and connected thereto, there being a passageway between 10 said nozzle member and the bore of the tubular member, the nozzle member and the front end of the head having a telescopic connection, means for packing the joint at said connection, and coöperating means carried 15 by the rear end of the tubular member and the seat for securing said member, and thereby the tip, to the head.
3. In a burner of the character described, the combination, with a head having a centrally arranged bore, an internally threaded seat in front of said bore, and a chamber in 20 front of said seat, of a removable tip comprising an inner tubular member the rear end whereof is threaded for application to 25 said seat and a nozzle member surrounding the front portion of said member and secured thereto, there being a passageway between 30 said nozzle member and the bore of the tubular member, and means coöperating 35 with the rear end of the nozzle and the front end of the head for forming a gas tight joint therebetween, the head being provided with a passageway communicating with said 40 chamber.
4. In a burner of the character described, the combination, with a body or shell having a centrally arranged bore, a seat in front of said bore, and gas supply connections leading to said bore and to a chamber 45 in front of said seat, of a removable tip comprising an inner tubular member and an outer nozzle, said nozzle and tubular member being rigidly connected and providing a passageway therebetween, means for 50 securing the inner member in said seat with the rear end of the nozzle telescopically fitting the front end of the shell, and a packing gland surrounding said nozzle and connected to the front end of the shell.
5. In a burner of the character described, the combination of an inner tubular member having an outwardly projecting body at its discharge or delivery end, said body being provided with slots extending inwardly 55 from the outer surface thereof and converging longitudinally toward the central portion of said member, said slots being rectangular in cross section, a nozzle surrounding said tubular member and engaging the outwardly projecting body and closing the 60 outer ends of said slots, and gas supply connections communicating with the nozzle and with the inner tubular member.
6. A cutting torch comprising a tip having an oxygen supply duct and a plurality of converging longitudinally extended passages for the delivery of a mixture of pre-heating gases grouped about the said duct, 65 said passages being substantially rectangular in cross-section and of restricted area whereby the slit cut by the torch will be narrow and the propagation of flame through the passages will be prevented.
7. In a burner of the character described, the combination of an inner tubular member and an outer member or shell surrounding and coöperating therewith, a gas supply connection leading to the inner member, the outer member or shell having a passageway leading thereto, said passageway having 70 a pair of longitudinally spaced ports, an injector plug removably mounted in said passageway and having a lateral port communicating with one of the aforesaid ports and a central passageway arranged to discharge in proximity to the other port, and a passageway leading to the last-mentioned port.
8. A burner comprising a head provided with a chamber for a mixture of oxygen and a combustible gas and having a lateral projection extending from said chamber, 80 said projection having a passageway therethrough leading to said chamber, the inlet portion of said passageway being enlarged and threaded, an injector threaded into the enlarged portion of the passageway and having an operating device accessible from the outside of said projection, said injector being provided with a central bore and a lateral port communicating with said bore 85 and said projection having a passageway leading to said port and a passageway leading to the enlarged part of the passageway in front of the injector.
9. A burner of the character described having a passageway for conducting a mixture of gases thereto, said passageway having a pair of longitudinally spaced ports therein, an injector threaded into said passageway and having a lateral port adapted to communicate with one of the aforesaid ports and having a central bore extending from its port and arranged to discharge in 90 proximity to the other passageway port, and a passageway leading to the last-mentioned port, said injector having an operating head outside the burner body and a packing interposed between said head and body.
10. A burner of the character described comprising a head having a central tubular member and a nozzle surrounding said member and forming a space therewith, the effective diameter of said tubular member being increased at the discharge portion there-

of and at a portion at the rear of such discharge point whereby said inner member may engage said nozzle at such enlarged portions and said portions being provided 5 with slots extending inwardly from the peripheries of such enlarged portions and being substantially rectangular in cross section and the slots converging toward the bore of the central tubular member.

10 11. A burner of the character described comprising a head having a central tubular member and a nozzle surrounding said member and forming a space therewith, the effective diameter of said tubular member being increased at the discharge portion thereof and at a portion at the rear of such discharge portion whereby said inner member may engage said nozzle at such enlarged portions and said portions being provided 15 with slots extending inwardly from the peripheries of such enlarged portions, the slots in the rear enlarged portion being of greater capacity and fewer in number than those in the enlarged front or discharge portion and the slots in the enlarged front portion converging toward the bore of the tubular member.

12. A burner of the character described comprising a head having a central tubular member and a nozzle surrounding said member and forming a space therewith, the effective diameter of said tubular member being increased at the discharge portion thereof and at a portion at the rear of such discharge point whereby said inner member may engage said nozzle at such enlarged portions and said portions being provided 20 with slots, the slots in the rear enlarged portion being of greater capacity and fewer in number than those in the enlarged front or discharge portion and the slots in the enlarged front portion converging toward the bore of the tubular member.

25

30

40

discharge portion and the slots in the enlarged front portion being substantially rectangular in cross section and converging toward the bore of the tubular member.

13. A cutting torch having in combination 45 a central axial passageway and a plurality of substantially rectangular passageways grouped about the central passageway and having their discharge ends in substantially the same plane as the discharge end 50 of the central passageway and converging toward the central axial passageway, means for supplying oxygen to the central axial passageway, and means for supplying a mixture of oxygen and a combustible gas 55 through the surrounding passageways.

14. A burner of the character described, comprising a head having a central tubular member, a nozzle surrounding said member and forming a space therewith, the effective 60 diameter of said tubular member being increased at the discharge portion thereof and at a portion at the rear of such discharge portion whereby said inner member may engage said nozzle at said enlarged 65 portions, said portions being provided with passageways, the passageways in the rear enlarged portion being of greater capacity and fewer in number than those in the enlarged front or discharge portion and the 70 passageways in the enlarged front portion converging toward the bore of the tubular member.

In testimony whereof, I hereunto affix my signature in the presence of two witnesses. 75

JOHN HARRIS.
